UNITED STATES PATENT OFFICE.

MAE NOEL, OF WASHINGTON, DISTRICT OF COLUMBIA.

PLAITING MACHINE.

Application filed February 21, 1923. Serial No. 620,551.

To all whom it may concern:

Be it known that I, MAE NOEL, a citizen of the United States, and a resident of Washington, in the District of Columbia, have invented certain new and useful Improvements in Plaiting Machines, of which the following is a specification.

This invention relates to a form pattern making machine.

10 The invention particularly relates to a machine for making form patterns of the character employed for plaiting skirts, ruffles, panels, etc., that is, for forming accord-
ion, side or knife, box plaits or the like used
15 in wearing apparel.

Patterns of the form above referred to are usually made of paper or the like having a suitable stiffness. The pattern consists of two layers crimped to correspond to the plait 20 desired and are arranged in such a manner that one or more layers of goods can be placed between them. When plaiting a piece of material one layer of the form pattern is stretched on a table. The material 25 is placed on this and the second pattern is placed on top, the lines of both patterns corresponding. The material may now be folded with the form patterns and then placed in a steam chest for a certain period. Upon 30 removing the form patterns and material from the steam chest the material will then have plaits similar to that of the form pattern. Also if desired the form patterns with material therein may be ironed instead 35 of placing the same in a steam chest with like results. This way of plaiting is well understood by those skilled in the art.

The object of the present invention is to 40 provide a machine by which form patterns of the character heretofore referred to may be made in an efficient and rapid manner and with a minimum of labor.

It is also an object of the invention that 45 the machine be automatic in operation relative to the crimping operation of the pattern.

It is a further and important object of the 50 invention that the machine be adapted for substitution of parts and adjustments whereby different form patterns may be produced or made.

It is also within the scope of the objects 55 of the invention that the machine be exceedingly simple in construction and easy to manipulate.

Other objects, and objects relating to de-

tails of construction, combination and arrangement of parts will hereinafter appear in the description to follow.

The invention is illustrated by way of example in the accompanying drawings, in which:—

Figure 1 is a view in side elevation of one side of the machine.

Figure 2 is a top plan view of the same. 65

Figure 3 is a longitudinal vertical sectional view of the machine taken substantially centrally thereof.

Figure 4 is a view similar to Figure 1 but illustrating the different working parts or 70 elements of the machine after the operation of the automatic stop.

Figures 5 and 6 are detail views in side elevation and partly in section illustrating, respectively, the two operations of the 75 crimping rollers and associated parts.

Figure 7 is a detail view in side elevation illustrating the driving means for the paper feeding mechanism.

Figure 8 is a detail view in side elevation 80 further illustrating the means for operating the automatic stop.

Figure 9 is a sectional view taken substantially on the line 9—9 of Figure 8.

Figure 10 is a detail sectional view illustrating the construction of the electrical switch employed in connection with automatic stop mechanism. 85

Figure 11 is a detail perspective view of the pivoted end portion of control arm. 90

Figure 12 is a sectional view taken substantially on the line 12—12 of Figure 11.

Figure 13 is a group view illustrating the manner in which a block member is slidably held within the control arm for the 95 automatic stop.

Figure 14 is a view in side elevation of another form of drive cam.

Figure 15 is a detail view in side elevation showing the control cam and pawl for 100 the proper feeding mechanism.

Figures 16, 17 and 18 are edge views of different forms of patterns which may be made with the present machine.

Like reference numerals refer to similar 105 parts in each of the several views.

Referring to the drawings in detail the machine may consist in a frame comprising the two side walls W and W' which may be secured together by the rods R, said rods 110 being preferably four in number and positioned as shown in the drawings. These

rods also serve to properly space the walls W and W' from one another.

Between the walls W and W' there is journaled the two shafts S' and S², said 5 shafts being preferably in horizontal alignment and occurring adjacent the upper ends of the walls. The shaft S² is forward to the shaft S'. Upon the wall W' there is mounted in a suitable manner an electric motor M, 10 said motor carrying upon its driving shaft a sprocket wheel 10 which is connected to a sprocket wheel 11 carried by the shaft S' through the means of a suitable sprocket chain 12. A sprocket wheel 13 is mounted 15 upon each of the shafts S' and S² which are operatively connected to each other by the means of a sprocket chain 14 whereby to impart the rotation of the shaft S' to the shaft S².

20 The shaft S² is extended from each of the walls W and W' and upon each end of the shaft there is mounted a cam wheel 15. Each cam wheel is in the form of a disc and having formed upon its inner surface a 25 circular groove 16 which is provided with the diametrically opposed depressions 17 and the two similarly opposed protrusions 18.

At a point between the walls slightly forward of the motor M there is journaled a 30 shaft S³ which carries a drum 19 upon which there may be placed a roller of paper R'. Forward of the shaft S³ there is suitably journaled between the walls W and W' a pair of rollers R², one of said rollers being 35 positioned above the other as shown, and the periphery of said rollers being so spaced that the continuous sheet of paper 20 constituting the roll of paper R' may pass between these rollers and be frictionally engaged thereby. The rollers R² are each supported by a pair of pins 21, the pins 21 associated with wall W being extended and each carrying a cog wheel 22. The cog 40 wheels 22 are adapted to be in constant mesh with one another. Forward of the rollers R² there is mounted a crimping unit comprising the two cross bars 23 which are so spaced that the sheet of paper 20 may pass therebetween. Each member 23 preferably 45 has its forward end beveled as at 24, and its rear end provided with an offset portion 25. The offset portions 25 should terminate in close relation to the periphery of the rollers R². Forward to the rollers R² each side 50 wall W and W' is provided with a pair of arcuate shaped slots 26' and 27', which intersect each other in each instance as at 26.

55 A pair of crimping rollers R³ and R⁴ are provided which are disposed between the walls W and W' and forward of the rollers R². The roller R⁴ is provided at each of its ends with a pin 29 (Figure 2), and each pin 29 is disposed in the associated slot 27'. The roller R³ is also provided at each end with 60 a pin 30 and each pin is disposed in the asso-

ciated slot 26'. The one end of a link member 31 is pivotally connected to each of the pins 29 of the roller R⁴ and the other end of each link 31 is pivotally connected to the associated side wall of the machine as at 32. 70 A similar link 33 is likewise connected to each end of the roller R³, and each link pivoted to the associated side wall of the machine as at 34. Similar ends of the rollers are connected by a link 37. Upon each side 75 of the machine there is provided an operating bar 35 for the rollers R³ and R⁴, said bar in each instance being pivotally connected at its lower end to the associated link 37 as at 38.

80 Each bar 35 is pivotally connected at its upper end as at 40 to a bar 41. The bar 41 is pivoted at its rear end as at 42 to the associated side wall of the machine and its forward end is provided with a suitable roller adapted to move in the associated groove 16, said roller being supported by the means of a pin or the like as at 43. The pivotal connection 40 of the bar 35 in each instance occurs adjacent the free end 90 of the bar 41.

95 The rollers R² are operated through the means of the cog wheel generally indicated at 44, said cog wheel being carried or formed integral with a ratchet wheel 47. The cog wheel 44 together with the ratchet wheel 47 are journaled upon a stub shaft 48, Figure 2, projecting from the side wall W of the machine. The cog wheel 44 occurs upon the inner side of the ratchet wheel 100 47. The ratchet wheel 47 is provided with teeth 49 approximately of the shape and size shown. The cog wheel 44 is in constant mesh with the lowermost associated cog wheel 22 whereby the rollers R² are 105 driven in opposite directions and thereby to draw the sheet of paper 20 therebetween.

110 The ratchet wheel 47 is driven by a reciprocating bar 50, said reciprocating bar being slidably held upon the side wall W of the machine by a suitable boxing 51 and carrying at its forward end a pawl 52 which is adapted to engage with the teeth 49 upon movement of the bar 50 in a rearward direction. Openings 53 are provided in the forward end of the bar 50 whereby the pawl 52 may be adjusted. The forward end of the bar 50 is pivotally connected as at 54 to the lower end of an actuating bar 55, said 115 actuating bar being pivotally connected as at 56 to the side wall W of the machine at a point substantially central of its length and at its upper end carrying a roller 57 which is disposed to move in a groove 58 formed upon the outer surface of a cam wheel 59. The cam wheel 59 is in the form of a disc and the groove 58 therein is formed with four protrusions, the two protrusions 60 being diametrically opposed to each other and the protrusions 61 being similarly 120 125 130

arranged. The cam wheel 59 is secured to the associated end of the shaft S' and is held against turning movement by the means of a key as at 62. This cam may be turnably 5 adjusted upon the shaft through the means of the different keyways shown in the hub of cam. This is also true of the cams 15. Upon the stub shaft 48 exterior to the ratchet gear wheel 47 there is pivoted an 10 arm 63, said arm being pivoted at a point intermediate its ends upon the stub 48 and its lower end is adjustably held by the means of a bracket member 64 which is secured to the wall W of the machine. The 15 bracket member 64 consists in an arcuate shaped member having its ends formed with offset portions 65 which are secured to the wall W of the machine, and between these end portions the member 64 is provided 20 with an elongated slot 66 extending substantially the entire length thereof. The lower end of the arm 63 has extending therefrom a suitable stud which is adapted to slide within the slot 66, and this stud has 25 threaded thereon a suitable wing nut 67 whereby the arm 63 may be adjustably held. Suitable markings may be made upon the member 64, as shown, in order to accurately adjust the member 63. The upper end of 30 the arm 63 carries a stub shaft 68 which in turn supports a collar or sleeve 69 of insulating material, said collar carrying a pair of slip rings 70. Suitably insulated contacts may be provided upon the upper 35 end of the member 63, not shown, and electrically connected to the slip rings 70, said connections being made upon the inner periphery of the slip rings. Turnably mounted upon the sleeve 69 is a cup-shaped casting 72, said casting having formed at 40 its free or outer end a flange plate 73 which terminates in an inwardly disposed flange 74. The casting 72 is held upon the stub shaft 68 by a pin 75, the inner and free end 45 of which extends into a groove 76 formed in the member 68. Upon the outer end of stub shaft 68 there is turnably supported a head or cap 77, the inner end of which terminates in ratchet teeth 78. A spring 50 pressed pawl 79 carried by the stub shaft 68 holds the head or cap 77 against turning in one direction. Within the casting 72 there is positioned a spiral spring 79' having its outer end secured to the casting as 55 at 80, and its inner end secured to the head 77. A plate 82 is fitted into the outer end of casting 72, said plate being rotatable about the head 77. The forward face of head 77 should be provided with a slot into 60 which a key may be positioned for rotating the same to wind the spring 79'. The plate 82 is secured to the casting 72.

Upon the flange portion 73 of the member 72 there is turnably mounted a switch casing generally indicated by the reference nu-

meral 83, said casing being cylindrical in shape and its one end formed with a reduced extension which extends through an opening in flange 73 and terminates in a head 84, whereby the casing may be manually rotated. A spring 84' yieldingly holds the casing against rotation. Within the casing 83 there is secured a contact finger 85, said finger having a free end portion 86 extending through a slot 87 in the wall of the casing. The portion 86 is depressible. A second contact making finger 88 is disposed within the casing and secured thereto and this contact member is adapted to normally engage the finger 85. Each finger 85 and 88 is connected to a brush 71 through suitable means as shown in Figure 9 whereby to permit turning of the casing 83 and also permit rotation of member 72. The motor M heretofore referred to should be connected so that its supply of electric current must pass through the contact fingers 85 and 88. The manner in which the motor might be connected is entirely apparent and therefore not shown.

Upon the arm 63 there is secured adjacent its one edge a bracket arm 89 which is formed at its outer end with a sleeve 90 through which there slidably extends a rod 91. It is important to here observe that the casting 72 is formed so that it is disposed concentrically to the stub shaft 68. This structure is best illustrated in Figure 9 of the drawings.

The inner end of the rod 91 carries a latch member 92 which is adapted to engage a protrusion or lug 93 formed upon the inner periphery of the flange 74 and thus to lock or hold the casting 72 against rotative movement when so urged by the spring 79. Adjacent the inner end of the rod 91 there is slidably mounted a sleeve 94 which is preferably square in cross section and which carries a set screw 95 by which the same may be adjusted upon the rod 91. The outer end of the rod terminates in a head 96 which in turn terminates in a body or semi-circular member 97; and between the head 96 and the sleeve 90 of the bracket arm 89 there is interposed a compression spring 98. The member 97 carried by the rod 91 is adapted to be engaged by a pin 99 carried by the ratchet wheel 47. The ratchet wheel 47 has a plurality of openings 99' whereby the position of pin 99 may be changed.

The plate 82 is formed with an annular groove 100 which is eccentric to stub shaft 68; and in which there is disposed a pin 101 carried by a block 101' which is slidable in a hollow arm 102, said arm being provided with a longitudinal slot 102' to accommodate the pin 101. The rear end of arm 102 is pivotally supported as at 103 adapted to permit free upward and downward swinging movement of said arm. The pivotal

support 103 also provides a pivotal support for the bar 104, which, adjacent its free end is provided with a downwardly curved portion 105 to provide a substantially arcuate 5 shaped edge surface 106 upon which the pawl 52 may ride. As shown in Figure 11, adjacent the pivoted end of the bar 104 there is formed a pair of diametrically opposed ears 107 to which there is secured a bridge 10 member 108, said bridge member having an intermediate portion 109 which is provided with an elongated slot 110. The arm 102 is adapted to move beneath the bridge portion 109, and said arm carries a bolt 111 15 which extends through the slot 110 and a similar slot 110' in a plate 111', which is slidable upon the bridge portion 109 of member 108. A stud 112' extends from the member 108 and through slot 111' in plate 111'. The stud 112' carries a wing nut 113' whereby the plate may be adjustably held. Beneath the bar 104 there is mounted a leaf 20 spring 113 which is pivoted at its one end to the side wall of the machine as at 114, 25 and which is held against downward swinging movement by a pin 114'.

Upon the side wall W of the machine there is rotatably supported a disc wheel 115, the periphery of which is formed with 30 a plurality of notches 116, said notches being preferably four in number as shown. The hub of the disc 115 is extended and this extension is formed with the four radial arms 118, each arm having slidably mounted 35 thereon a circular member 119, 119^a, 119^b and 119^c respectively. Preferably each radial arm 118 has graduations thereon as shown so that the members 119, 119^a, 119^b and 119^c is adapted to engage the upper edge 40 of the bar 104 when brought into proper position by the rotation of the disc 115. A pawl 120 is pivotally supported by the reciprocating bar 50 and supported by a rest 121. The pawl 120 will engage the wheel 45 115 upon movement of the bar 50 in one direction.

Referring to Figures 16, 17 and 18, 122 indicates in each figure a pair of patterns and 50 123 the material therebetween. Further explanation relative to forming these patterns will later be given.

In Figure 17 each side plait comprises 55 two plies of sheet material 126 and 126' and the box a single ply of sheet material 127. Ply 126 is of less width than ply 126'. Assuming it is intended to make the pattern shown in Figure 17, the sheet of paper constituting the roll of paper R' is extended 60 between the rollers R² and also extended further forward and between the crimping bars 23. The members 119 and 119^b are so adjusted that when they come in contact with the bar 104, its curved portion 106 will be in such a position that the power stroke of 65 pawl 52 will be partially lost, and the rol-

lers R² will feed the paper a distance equal to the width of ply 126'. Members 119^a and 119^c are so adjusted that when they come into contact with bar 104, its curved portion will be brought to such a position 70 that a greater part of the power stroke of pawl 52 will be lost and cause rollers R² to feed the paper a distance equal to width of ply 126. The arm 63 should be adjusted and pin 99 positioned in one of the openings 75 99'.

After these adjustments have been made, motor M may be started and let it be further assumed that upon the starting of said motor, the position of the arm 55 is as 80 shown in Figure 1, and that also the position of the bars 35 is as illustrated in this figure. The motor should rotate in such a direction that the cam wheels 15 and also the cam wheel 59 will rotate in an anti-clockwise direction. 85 With the rotation of the shafts S' and S², the arm 55 will first be actuated and the bar 50 moved forward to its extreme forward position when the roller 57 of the arm 55 is disposed in one of the protrusions 61 90 of the groove 58. The pawl 120 will also during this interval rotate the disc wheel 115 so that the member 119 will engage the bar 104 and swing the same downwardly a certain degree. The amount which the arm 95 will be swung downwardly is as illustrated in Figure 7 of the drawings.

As seen in dotted lines in this figure, the pawl 52 is at the extreme forward position 100 and due to its width the same will rest on the curve portion 106 of bar 104. Now as the roller 57 of the bar 55 moves from the protrusion 60 of the groove 58, the reciprocating bar 50 will move rearwardly and the pawl 52 after losing part of its stroke on curve portion 106 will come in contact with teeth 49, thereby causing the ratchet wheel 47 to rotate in an anti-clockwise direction whereby the rollers R² are rotated to draw the paper from the roll R forwardly a distance equal to the width of ply 126', Figure 17. After the roller 57 of the arm 55 is clear of the protrusion 60 a crimping operation will take place of the paper disposed between the crimping members 23. At this interval the rollers 43 carried by the bar 41 105 will enter in one of the protrusions 18, and thereby raise the bar 35. With this happening the pins of the roller R⁴ will move into the upper end portion of the slots 27', and the pins journaling the roller R³ will move into the upper end portion of the slots 26' and during this movement will roll upon the arcuate surface 24 of the crimping member 23, and thus cause a crimp of paper as 115 illustrated in dotted lines of Figure 5. During this operation the cams 15 continue to revolve and the rollers 40 move out of protrusions 18. In this way the crimping rollers are permitted to return to original posi-

120 125 130

- tion. As the operation of the machine continues the roller carried by the arm 55 will move into one of the protrusions 61 and again reciprocate the bar 50, causing pawl 120 to rotate disc wheel 115 and causing member 119^a to adjust curved portion 106 of bar 104 so that pawl 52 will lose part of its stroke on curve portion 106 of bar 104 before coming in contact with teeth 49 thereby causing the rollers R² to feed the paper a distance equal to ply 126, Figure 17, between members 23. Now as the roller 57 of arm 55 passes protrusion 61 roller 43 of arm 41 will move into a depression 17, as indicated in dotted lines in Figure 6 of the drawings and with this occurring the pin journaled in the roller R³ will move into the lower end portion of slots 26', while the pins journaling in the roller R⁴ will move into the lower end portion of slots 27', and with this movement will roll upon the arcuate surface 24 of the crimping member 23, and thus crimp the paper in the opposite direction. As the machine continues to operate member 119^c will next actuate a crimp similar to the first crimp made and member 119^b, a crimp similar to second crimp made, etc., making the pattern with side plaits until stopped by pin 99 striking member 97 carried by rod 91. When the pin 99 strikes member 97 carried by rod 91, the rod 91 is pushed forward and the member 72 released. This member 72 will revolve under the force of the spring 76 one-half turn or until the switch casing 83 engages the sleeve 94 carried by rod 91. This casing is so held by spring 84' that the depressible portion of finger 86 will be pressed in by sleeve 94 and open the circuit of motor M to stop the machine. When member 72 revolves this half turn under the force of spring 76, pin 101, in groove 102' follows eccentric groove 100 moving bar 102 downward and carrying with it bar 104 due to pin 111 as shown in Figure 4, thus giving a greater stroke on the teeth 49 of the gear wheel 47.
- By adjusting arm 63 before starting machine, the position of pin 101 may be changed with respect to arm 102 and as is apparent this adjustment will regulate the width of box plaits. Disk 15 is now manually moved from position as shown in Figure 5 to position as shown in Figure 6 or vice versa, as sometimes is the case causing the crimp at each side of the wide box to be made in the same direction. In the operation of this automatic stop and large plait regulator, one of the strokes of one of the members 119^a or 119^c or disc wheel 115 is lost as bar 102 has carried bar 104 below the reach of the member. The machine may be started by manually turning member 83, releasing arm 86, and thus making the electric circuit for motor M.
- On turning the member 83 by head 84 the motor circuit is again established. The pawl 52 takes its long power stroke and pin 99 depresses member 97 a sufficient distance to permit pin 99 to slide beneath 97 and permits rod 91 to return to original position and thereby release member 83 and permit casting 72 to return to its original position. The turning of casting 72 is stopped by latch member 92 engaging lug 93. The machine may now be operated to complete the pattern. In this last operation the short ply 126 is first made and the ply 126', etc., as shown in Figure 17.
- In making an accordion plait pattern as shown in Figure 18 pin 99 is removed, thus the automatic stop and long plait regulator is not used. Members 119, 119^a and 119^b and 119^c are adjusted alike, and all plaits will be of the same width. Another way to make all plaits the same size is to set bar 104 so that pawl 52 will not engage the same and adjust pawl 52 to produce the width desired.
- In making a box plait pattern as shown in Figure 16, the automatic and wide plait regulator are not used. In this instance, members 119 and 119^b on disk 115 would be set for the longest power stroke of pawl 52. Members 119^a and 119^c for the shortest stroke. Cam wheels of the form shown in Figure 14 are substituted for cam wheels 15 in order to produce the proper creasing for a pattern of this kind.
- Other plaits or combination of plaits can be made as the one way side which is the same as the plaits on either side of the box in Figure 17 or combinations can be made by using a plurality of pins 99.
- It may be here noted that the roll carrying the material or paper from which the forms are made might be arranged to release or give off two or more sheets and thus to produce two or more forms with one operation of the machine. This is entirely apparent, and no structure need be shown to illustrate the same. Referring to Figures 2 and 3, at 131 is indicated a trough for water. This trough extends transversely of the paper 20 and with this trough, there is associated a wick 132 which engages the sheet of paper 20 therebeneath. It has been found the wick 132 will moisten the paper and prevent cracking of the fibre therein during crimping operations.
- While I have herein shown and described the preferred form of my invention, I wish it to be understood that I am aware of the fact that the construction, combination and arrangement of parts may be changed by those skilled in the art without departing from the spirit of the invention as indicated by the appended claims.
- What I claim is:
1. In a device of the character described, a pair of stationary members, each having

an arcuate surface and said members being arranged parallel and spaced suitably for feeding a sheet of paper therebetween, and a pair of connected rollers adapted to move 5 over the arcuate faces of said stationary members and transversely crimp the paper passing therebetween.

2. In a machine of the character described, a frame, a pair of stationary members positioned in said frame, said members extending parallel to each other and spaced a sufficient distance to permit the passage 10 of a sheet of paper therebetween, each stationary member having its forward face 15 formed with an arcuate transverse surface, a pair of rollers forward of the stationary members, and means whereby said rollers may be moved for crimping the paper fed between said stationary members in opposite 20 directions.

3. In a machine of the character described, a pair of stationary members, means for feeding a sheet of paper between said members, a pair of rollers forward of the stationary members between which the paper may pass, and means for moving the pair of rollers whereby the same will cooperate with the forward edges of the stationary member to crimp the paper transversely and in opposite directions.

4. In an apparatus of the character described, a pair of crimping members, means for feeding a sheet of material between said members and forwardly with respect thereto, and a pair of angularly movable rollers adapted to cooperate with said crimping members whereby to crimp said sheet of flexible material transversely and in opposite directions.

40 5. In an apparatus of the character described, a pair of stationary members between which a sheet of flexible material may be passed, and a pair of angularly movable and interconnected members forward of said stationary members adapted to cooperate with the forward faces of said stationary members for crimping the flexible material transversely and in opposite directions.

50 6. In an apparatus of the character described, a pair of stationary members, each having its forward face arcuate in shape, means whereby a sheet of flexible material may be fed between said members and forwardly with respect thereto, a pair of rollers, each roller being adapted to operate upon the forward face of one of said crimping members for crimping the paper being passed therethrough transversely and in opposite directions.

60 7. In an apparatus of the character described, a pair of stationary crimping members between which a sheet of flexible material may be passed, each member having its forward face arcuate in shape, a pair of

rollers, each of which is adapted to operate upon the forward face of one of said crimping members for crimping the paper passed therethrough transversely, and connecting means between said rollers whereby when 70 one roller is moved for crimping the paper, the other roller will be moved to an inoperative position.

8. In an apparatus of the character described, a pair of stationary crimping members between which a sheet of flexible material may be passed, each member having its forward face arcuate in shape, a pair of rollers, each of which is adapted to operate 75 upon the forward face of one of said crimping members for crimping the paper passed therethrough transversely, and link connections between said rollers whereby with the movement of one roller for crimping the flexible material the other roller will be 80 moved to an inoperative position.

9. In an apparatus of the character described, a pair of rollers between which a sheet of flexible material may be passed, a gear wheel adapted to rotate said rollers 90 for moving the paper forwardly with the rotation thereof, means for rotating the gear intermittently, and means forward of the rollers for crimping the paper transversely during each movement of said rollers.

10. In an apparatus of the character described, a pair of rollers between which a sheet of flexible material may be passed, a gear wheel adapted to rotate said rollers 100 for moving the paper forwardly with the rotation thereof, means for rotating the gear intermittently, and means forward of the rollers for crimping the flexible material being passed between said rollers transversely and alternately in opposite directions.

11. In an apparatus of the character described, a pair of rollers between which a sheet of flexible material may be passed, a gear wheel adapted to rotate said rollers for moving the paper forwardly with the rotation thereof, means for rotating the gear intermittently, means forward of the rollers for crimping the flexible material being passed between said rollers transversely and alternately in opposite directions, means for automatically bringing the gear to a stop, and means whereby one or more crimping operations may be obviated thereby to permit a section of the flexible material to pass 110 said crimping means without being operated upon.

12. In an apparatus of the character described, a pair of stationary members between which sheet material may be fed, and means adapted to alternately operate upon the forward faces of the stationary members for crimping the material in opposite directions.

13. In a device of the character described, 120 a feeding mechanism, including in combina-

- tion, a ratchet wheel, a reciprocating bar, a pawl carried by said bar adapted to engage the teeth of said ratchet wheel when said bar moves in one direction, a bar pivotally supported at its one end and positioned adjacent the peripheral edge of said ratchet wheel at its other end, said bar being adapted to cause the pawl to ride thereon and limit the number of teeth of the ratchet wheel said pawl will engage of the ratchet wheel upon each operative movement of the reciprocating bar.
14. In a device of the character described, a feeding mechanism, including in combination, a ratchet wheel, a reciprocating bar, a pawl carried by said bar adapted to engage the teeth of said ratchet wheel when said bar moves in one direction, a bar pivotally supported at its one end and positioned adjacent the peripheral edge of said ratchet wheel at its other end, said bar being adapted to cause the pawl to ride thereon and limit the number of teeth of the ratchet wheel said pawl will engage upon each operative movement of the reciprocating bar, means whereby the last named end of the pawl controlling bar may be depressed at timed intervals and thereby to increase the number of teeth the pawl engages upon said ratchet wheel.
15. In a device of the character described, a feeding mechanism, including in combination, a ratchet wheel, a reciprocating bar, a pawl carried by said bar adapted to engage the teeth of the ratchet wheel upon movement of the bar in one direction, a pawl controlling bar pivotally supported at its one end and its other end having a curved surface upon which the pawl may ride, and means to depress said pawl controlling bar at timed intervals whereby to increase or decrease the rotative movement imparted to said ratchet wheel upon each operative engagement thereof by said pawl.
16. In a device of the character described, a feeding mechanism including a ratchet wheel, a reciprocating bar, power means for reciprocating said bar, a pawl carried by said bar adapted to engage the ratchet wheel and rotate the same upon movement of the bar in one direction, means whereby each rotative movement of the ratchet wheel may be controlled, and means whereby the power means may be automatically rendered inoperative and the feeding mechanism brought to a stop at a predetermined interval.
17. In a device of the character described, a feeding mechanism including a ratchet wheel, a reciprocating bar, power means for reciprocating said bar, a pawl carried by said bar adapted to engage the ratchet wheel and rotate the same upon movement of the bar in one direction, means whereby each rotative movement of the ratchet wheel may be controlled, and means carried by the ratchet wheel adapted to serve for automatically rendering the driving power inoperative and bringing said feeding mechanism to a stop.
18. In a device of the character described, a feeding mechanism including a ratchet wheel, a reciprocating bar, power means for reciprocating said bar, a pawl carried by said bar adapted to engage the ratchet wheel and rotate the same upon movement of the bar in one direction, means whereby each rotative movement of the ratchet wheel may be controlled, and adjustable means carried by said ratchet wheel and adapted to operate for rendering the driving power inoperative and bringing said feeding mechanism to a stop.
19. In a device of the character described, a pair of stationary members, said members being arranged to permit the feeding of sheet material therebetween, a pair of connected rollers adapted to be moved over the faces of said stationary members for crimping the material being fed therebetween at timed intervals, and means for operating said rollers including cam and link means adapted to cooperate for actuating said rollers at the proper intervals.
20. In a device of the character described, a pair of stationary members, said members being arranged to permit the feeding of sheet material therebetween, a pair of connected rollers adapted to be moved over the faces of said stationary members for crimping the material being fed therebetween at timed intervals, means for operating said rollers including cam and link means adapted to cooperate for actuating said rollers at the proper intervals, and means whereby said cams may be adjusted whereby to change the crimping moment of said rollers.

MAE NOEL.
